PAPER MAKING MACHINE

Gerould T. Lane and Wendell Butterfield, Rochester, N. Y., assignors, by mesne assignments, to Eastman Kodak Company, Jersey City, N. J., a corporation of New Jersey

Application November 20, 1934, Serial No. 753,919

11 Claims. (Cl. 92—43)

This invention relates to machines for making paper and particularly to machines in which the stuff can be mixed with an extremely large quantity of water.

5 One object of our invention is to provide a machine of the type described in which a cylinder is used to support one end of the paper making wire, this wire passing partially around and to and from the cylinder. Another object of our 10 invention is to provide a machine in which the cylinder is partially submerged in a flow box so that the making wire passing around the cylinder can receive a very substantial deposit of fibers, and so that an additional but continuous deposit 15 of fibers can take place on the making wire as it leaves the cylinder. Another object of our invention is to provide a machine in which the speed of the flow of stuff can be maintained at substantially the speed of the making wire and 20 in which the quantity of the flow over the making wire as it leaves the cylinder can be controlled. Another object of our invention is to provide a flow divider for dividing the stuff in the flow box into two streams in both of which 25 the stuff remains continuously moving, and in which concentration of the fibers is prevented. Another object is to provide a flow box to and from which a making wire and the deckle straps are passed and to provide a flow box with a suitable 30 seal through which the making wire and deckle straps may pass. Other objects will appear from the following specification, the novel features being pointed out in the claims at the end thereof.

35 Coming now to the drawings wherein like reference characters denote like parts throughout:

Fig. 1 is a side elevation partially in section of a machine constructed in accordance with and embodying a preferred form of our invention.

Fig. 2 is a fragmentary section on line 2—2 of Fig. 1.

Fig. 3 is an enlarged fragmentary detail partially in section showing the flow box seal for the making wire and deckle straps.

Fig. 4 is a section on line 4—4 of Fig. 1.

Fig. 5 is a fragmentary plan view of a deckle stuffing box.

50 It is well known in the paper making art that it is desirable to use a large quantity of water relative to the fibers in the stuff in order to lay the fibers evenly and without definite pattern upon the making wire. However, the 55 quantity of water which can be used is largely

controlled by the amount of water which can be removed from the wire.

In our co-pending application Serial No. 699-776, filed November 25, 1933, for Paper making machine, we have shown a machine in which 5 extremely large quantities of water can be removed successfully, and the present invention is for an improvement over the machine shown in this application.

It is desirable to move the stuff through a flow 10 box at substantially the same speed as the making wire and cylinder so that an even layer of fibers can be deposited upon the wire and so that these fibers will not lie parallel to the direction of movement of the wire.

With a machine of the type described in our co-pending application and of the type shown herein, where the fibers are deposited beneath the surface of the stuff in the flow box as well as being deposited on the wire as it leaves the 20 cylinder, it is very desirable to maintain the flow of stuff over the cylinder at the same speed of movement as the stuff moving about the submerged portion of the cylinder, and it is also desirable to have a large quantity of stuff in 25 the flow box so that as the wire leaves the cylinder, the consistency of the stuff will remain the same and will not become more concentrated.

We have found that by dividing the large quantity of stuff in the flow box into two streams and by utilizing all of one stream to flow out over the top of the paper wire, an improved product can be obtained. There are a number of advantages in using a flow divider, among which is the fact that the second stream of stuff, which does not 35 flow out over the making wire, can be used in a number of ways to obtain desired results. If this second stream is moved continuously out through an overflow, it will tend to retain an even flow of stuff through the entire flow box 40 and it will prevent the concentration of stuff near the paper making wire which so often causes lumps to collect. By utilizing an overflow, eddies and currents in the stuff which usually occur near the overflow can be prevented 45 from harming the deposit of fibers laid on the sheet because any such eddies will be separated from the paper making wire by means of the flow divider. Thus, the current or flow of the stuff through the first stream is not disturbed in 50 any way by the overflow.

Another advantage of having the stuff divided into two streams is that by controlling the level of the second stream, the head or pressure which forces a large part of the water through the mak- 55

ing wire as it passes around the cylinder can be controlled.

Referring particularly to the drawings, wherein an embodiment of our invention is shown, the 5 paper making machine may consist of a cylinder 1 which has a foraminous periphery and which may be of any well known type. This cylinder 10 may be supported by spokes 2 from a hub 3 and a hollow shaft 4 may rotatably support the cylinder 1 at least partially submerged in a flow box 5. This flow box may be of more or less 15 irregular contour and may consist of a curved wall 6 leading to a channel 7 which is divided by baffles 8 so that the stuff flows in through a pipe 9 from head box 10.

The wall 6 may be provided with an overflow 11 in which a slice 12 is adjustably mounted so that it may be moved by the hand-wheel 13 to raise and lower the level 14 of the stuff 15 in 20 the flow box. Thus, by turning the hand-wheel 13, the level can be varied and because of the flow 25 divided, the change of level of the stream 16 of stuff, which does not flow out over the making wire 17, causes more or less pressure upon the wire passing around the cylinder and a greater or lesser deposit of fibers thereon. The level of the stock flowing over the wire at 18 is raised somewhat by an increase of pressure, but this can be controlled by the hand-wheel 28.

30 We provide a flow divider 20 which is preferably in the form of an arcuate plate having side flanges 21, as best shown in Fig. 2, which lie flat against the side walls 23 of the flow box 5. This flow divider is pivoted upon a shaft 24 and the 35 upper end carries ears 25 slotted at 26 to receive a pin 27 which is vertically adjustable by means of the hand-wheel 28. The flow divider is provided with an upstanding flange 29 which serves as a dam so that if the level 14 of the stream 16 40 of stuff is raised by raising the slice 12, that end of the stream 16 which is toward the making wire will be held back by the flange 29.

It is not necessary that the flanges 21 and 29 be perfectly sealed against the side walls 23 of the flow box, but they should be sufficiently tight 45 to prevent any material flow of stuff between the edges of the flow divider and the flow box.

By moving the hand-wheel 28, the stream 19 of 50 stuff which passes out over the making wire 17 can be accurately controlled to the exact quantity of stuff which is required. In a machine of this type wherein the greater portion of the fibers have been laid upon the making wire 17 before it passes from the cylinder 1, the amount of stuff 55 which is flowed out over the making wire as it leaves the cylinder is relatively important because it is desirable to flow out just enough stuff to complete the desired thickness of the fibers laid on the wire, and the flow must not be cut down to such an extent that insufficient stuff is 60 flowed over the wire to prevent "wash-off" marks which have heretofore been the great difficulty with this type of machine.

The making wire 17 passes over a series of 65 guide rollers 30 which may be of any known type and the width of the fibers laid on the wire is controlled by the usual deckle straps 31. These straps are shown as being passed over guide rollers 32, 33, 34, 35, 36, and 37, although obviously 70 more rollers may be employed, if desired.

However, from rollers 37 the deckle straps 31, as best shown in Fig. 3, pass through a stuffing box 38 which is preferably lined with felt pads 39. These pads, when wet, form a very satisfactory stuffing box for the deckle straps and ef-

fectually seal the upper wall 40 of the flow box 5 so that stuff beneath this wall will not leak out. As shown in Fig. 5, there are four of these pads 39, one arranged on each side of the deckle strap. 5

The making wire 17 is an endless one which passes away from the cylinder towards and over a guide roller diagrammatically shown as 41 and then back toward the cylinder again passing around the guide roller 42. This guide roller directs the making wire to the cylinder 1 and it follows the cylinder around, being sealed from the flow box section indicated at 43 in the following manner: A flange 44 extends downwardly from the flow box wall 45 and supports a plate 46. This plate is preferably somewhat resilient and 15 can be conveniently made of sheet stock, such as stainless steel or chromium-plated brass. To the flexible plate 46 is attached a casting 47 having a flange 48 supported by brackets 49, and this plate is preferably provided with a rabbet 50 in 20 which the upper edge of a flexible plate 51 may lie and may be attached by rivets, screws, or other fastening means 52. The plate 51 should be flexible and should be made of a material which does not wear the making wire 17 more 25 than is absolutely necessary. We have found that formica is an entirely satisfactory material for the plate 51, this being relatively soft with respect to the making wire and yet being sufficiently strong and flexible to wear satisfactorily. 30

The flange 48 of member 47 is to permit the angular inclination of the plate to be changed, since one or more screws 53 passing through threaded nuts 54 may impinge upon the flange. By turning the head 55 of the nut, the flange 48 35 will cause the plate 47 to move. This movement is permitted by the flexibility of the plate 46 on one side of plate 47 and by the flexible plate 51 on the other side of the plate 47. Thus, the contact pressure of the formica plate 51 upon the 40 making wire 17 can be easily adjusted.

This adjustment usually only needs to be made once for the initial setting up of the machine, although, of course, it can be altered at any time if it should be desirable. However, the 45 pressure upon the plate 51 is not entirely due to the adjustment of the screw head 55 because the flow of stuff through the flow box tends to force the plate 51 against the making wire so that the flow of the stuff alone may be sufficient 50 to make a relatively tight connection and to prevent the stuff from passing up through the opening in the flow box through which the making wire is admitted.

After passing through the stuffing boxes 38, 55 the deckle straps 31 are sealed further against the sides 23 of the flow box by means of felt pads 56. These pads extend down some distance so that, as shown in Fig. 3, they will insure sealing the edges of the deckle straps 31 60 past that point 57 where the end of the formica sheet 51 contacts with the making wire 17. This effectively seals the sides of the vat so that the stuff is confined to its proper channel through the flow box. 65

I prefer to provide the felt pads 56 with slots 58 through which bolts 59 pass, so that in setting up the machine, these pads may be slid up against the edges of the deckle straps 31 and a relatively tight seal can be quickly provided. 70

The operation of our machine is as follows: Stuff flows through the flow box in the direction indicated by the arrows in Fig. 1. As the making wire 17 passes out from beneath the flexible seal 51 and as the deckle straps 31 pass 75

through their stuffing boxes and pass the side seals 56, the stuff flowing with the making wire and deckel straps at substantially the same speed starts to deposit fibers upon the making wire. This is due to the pressure or head caused by the elevation of the stuff in the flow box. Water is drained from the interior of the cylinder 1 as through a pipe 60, which may be provided with a valve to adjust the flow from the cylinder, if desirable. As the stuff and making wire proceed around through the flow box, the flow of stuff is divided into two streams 16 and 19 by the flow divider 20. The stream 19 flows out over the top of the making wire 17 as it leaves the cylinder 1 and deposits a fine, even, and continuous layer of water and fiber on the fibers already laid on the wire, thus effectually preventing "wash-off" lines or markings.

The stream 16 of stuff which flows on the opposite side of the flow divider flows out over an overflow so that the flow through the flow box is continuous and even. If the upper surface 14 of the stream 16 should become turbulent, or if there should be eddies or currents in this portion of the flow, the stock passing to the making wire will not be affected because it is divided from the stream 19 by the flow divider 20. Thus, any lumps or irregularities in the consistency of the stock in the stream 16 are immaterial.

The stuff may pass over the overflow 11 and out through a pipe 61 from which it may be re-beaten, although in practice we have found that the consistency of the stuff permits this to be pumped back into the head box 10 and recirculated, if desired.

The speed with which the fibers can be laid on the making wire passing about the cylinder can be controlled by the elevation of the adjustable slice 12 to the overflow. The greater the elevation of the stuff in stream 16, the greater the pressure upon the stuff in the flow box 5 so that the water will be forced more quickly through the making wire into the cylinder.

By adjusting the hand-wheel 28, the required amount of flow in stream 19 can be controlled so that the uniformity of the fibers passing out on the making wire from the drum can also be controlled. Although a comparatively heavy layer of fibers has been laid on the wire before it passes from the drum, the usual amount of fibers can be laid on the wire as it leaves the drum so that, if desired, a comparatively thick sheet of paper can be formed.

However, it is not primarily for the thickness of the sheet that we have designed this machine, but for the accurate control of the fibers so that an extremely strong and uniform sheet can be easily made—strong, because fibers of greater length than usual can be used, because of the large quantity of water which is used with this machine, and uniform, because the fibers which are laid on the making wire suffer very little from the usual difficulty of being directional with respect to the movement of the making wire. In other words, the fibers are laid on the making wire quite uniformly and in practically all directions, although, if the making wire and stuff in the flow box move at materially different speeds, as may be the case with careless adjustments, the fibers may be somewhat directional.

What we describe as our invention and desire

to be secured by Letters Patent of the United States is:

1. In a paper making machine, the combination with a cylinder, of a making wire and deckel straps extending partially around and to and from the cylinder, a flow box in which the cylinder is mounted, means for sealing the deckel straps and wire at their point of entrance into the flow box comprising a flexible plate extending across and contacting with the making wire, 10 felt pads adapted to seal edges of the deckel strap and forming a separate stuffing box for the deckel straps passing into the flow box, and a flow divider located on an opposite side of the cylinder from the side from which the making 15 wire and deckel straps enter the flow box.

2. In a paper making machine the combination with a cylinder, of a making wire and deckel straps extending partially around and to and from the cylinder, a flow box in which the cylinder is mounted, means for sealing the deckel straps and wire at their point of entrance into the flow box comprising a flexible dam including a flexible plate, a rigid plate attached to an edge thereof, a flexible plate connected to an edge of 25 the rigid plate and having an opposite edge resting on the making wire in a substantially tangential relation thereto.

3. In a paper making machine the combination with a cylinder, of a making wire and deckel 30 straps extending partially around and to and from the cylinder, a flow box in which the cylinder is mounted, means for sealing the deckel straps and wire at their point of entrance into the flow box comprising a flexible dam including a flexible plate, a rigid plate attached to an edge thereof, a flexible plate connected to an edge of the rigid plate and having an opposite edge resting on the making wire in a substantially tangential relation thereto, and means for 40 flexing the dam to move it relatively to the cylinder.

4. In a paper making machine the combination with a cylinder, of a making wire and deckel straps extending partially around and to and from the cylinder, a flow box in which the cylinder is mounted, means for sealing the deckel straps and wire at their point of entrance into the flow box comprising a flexible dam including a flexible plate, a rigid plate attached to an edge thereof, a flexible plate connected to an edge of the rigid plate and having an opposite edge resting on the making wire in a substantially tangential relation thereto, and a screw 55 passing thru the flow box, adjustable from the outside thereof and contacting with the rigid plate to flex the dam.

5. In a paper making machine the combination with a cylinder, a making wire extending partially around and to and from the cylinder, deckel straps associated with the making wire for controlling the width of the paper web, a flow box, pivotal supports for the cylinder carried by the flow box, said flow box including an entrance 60 opening for the making wire and deckel straps, means included in said opening for sealing the deckel straps and making wire to make a substantially fluid tight connection whereby a head may be maintained in the flow box, a flow divider 65 in the flow box for dividing the stuff into two streams and means for varying the level of one stream relative to the other to control the quantity of stuff in one of said two streams, whereby all of the stuff passing through one stream may

flow out over the top of the making wire as it moves from the cylinder.

6. In a paper making machine the combination with a cylinder, a making wire extending partially around and to and from the cylinder, deckel straps associated with the making wire for controlling the width of the paper web, a flow box, pivotal supports for the cylinder carried by the flow box, said flow box including an entrance opening for the making wire and deckel straps, means included in said opening for sealing the deckel straps and making wire to make a substantially fluid tight connection whereby a head may be maintained in the flow box, a flow divider in the flow box for dividing the stuff into two streams and means for regulating one stream relative to the other whereby one stream may be controlled as to quantity and speed of flow to co-operate with the movement of the making wire, and may flow out over the top of the making wire as it moves away from the cylinder.

7. In a paper making machine, the combination with a cylinder, of a flow box in which the cylinder is revolvably mounted, a making wire adapted to move with the cylinder passing around a part of the cylinder and being adapted to pass to and from the cylinder, said wire being guided from the cylinder in a substantially horizontal run, a flow divider mounted in the flow box for dividing the stuff in the flow box into two streams, one stream adjacent the cylinder being adapted to flow out over the top of the making wire as it passes from the cylinder.

8. In a paper making machine, the combination with a cylinder, of a flow box in which the cylinder is revolvably mounted, a making wire adapted to move with the cylinder passing around a part of the cylinder and being adapted to pass to and from the cylinder, said wire being guided from the cylinder in a substantially horizontal run, a flow divider mounted in the flow box for dividing the stuff in the flow box into two streams, one stream adjacent to the cylinder and the other stream spaced from the cylinder, and means for utilizing the second mentioned stream for controlling the fibers laid on the cylinder, the stream adjacent the cylinder flowing out over the

top of the making wire as it passes from the cylinder.

9. In a paper making machine, the combination with a cylinder, of a flow box in which the cylinder is revolvably mounted, a making wire adapted to move with the cylinder passing around a part of the cylinder and being adapted to pass to and from the cylinder, said wire being guided from the cylinder in a substantially horizontal run, a flow divider mounted in the flow box for dividing the stuff in the flow box into two streams, one stream adjacent the cylinder being adapted to flow out over the top of the making wire as it passes from the cylinder and means for varying the position of the flow divider relatively to the cylinder whereby all of the fibers in one of the divided streams may be deposited in the making wire, and may flow out over the top of the making wire as it passes from the cylinder.

10. In a paper making machine, the combination with a cylinder, of a wire passing partially around and to and from the cylinder, a flow box in which the cylinder is mounted, a stock divider for separating the flow of stock into two streams, said stock divider including a pivotal support on one end and means for adjusting the other end of the stock divider to and from the top of the cylinder whereby the proportions of the flow on both sides of the stock divider may be controlled, one stream of stock being adjacent the cylinder and flowing out over the top of the making wire as it moves away from the cylinder.

11. In a paper making machine, the combination with a cylinder, of a wire passing partially around and to and from the cylinder, a flow box in which the cylinder is mounted, a stock divider for separating the flow of stock into two streams, said stock divider being approximately concentric with the surface of the cylinder, an upwardly extending flange on one end of the stock divider adapted to form a dam for stock flowing on one side of the stock divider and means for alternating the distance between that end of the stock divider which includes the dam and the surface of the drum.
